UNITED STATES PATENT OFFICE

137,158

DESIGN FOR A TIGHTENING BAR FOR AN EMBROIDERY MACHINE

Theodore M. Berger, Ridgefield, N. J.

Application May 5, 1943, Serial No. 110,124

Term of patent 14 years

To all whom it may concern:

Be it known that I, Theodore M. Berger, a citizen of the United States of America, residing in Ridgefield, county of Ridgefield, and State of New Jersey, have invented a new, original, and ornamental Design for a Tightening Bar for an Embroidery Machine, of which the following is a specification, reference being had to the accompanying drawing, forming part thereof.

Fig. 1 is a front perspective view of a tightening bar for an embroidery machine, showing my new design.

Fig. 2 is a rear perspective view thereof.

I claim:

The ornamental design for a tightening bar for an embroidery machine, substantially as shown.

THEODORE M. BERGER.
